UNITED STATES PATENT OFFICE.

ARTHUR W. HULSON, OF KEOKUK, IOWA.

GRATE.

998,247.

Specification of Letters Patent. Patented July 18, 1911.

Application filed July 28, 1908. Serial No. 445,775.

To all whom it may concern:

Be it known that I, ARTHUR W. HULSON, a citizen of the United States, residing at Keokuk, in the county of Lee and State of Iowa, have invented certain new and useful Improvements in Grates, which the following is a specification.

My invention relates to an improvement in grates, and more particularly to the class 10 known as rocking fire grates used in steam plants and other plants where a large coal fire is maintained; and the object is to provide means whereby the grate sections are removably held upon the grate bar.

15 A further object is to provide means whereby the grate bar and grate sections can all be removed from the side bars or grate frame without in any wise interfering with the other grate sections or grate bars or 20 grate frame.

Another object of the invention is in the manner of attaching grate sections to the bar whereby a new grate section can be placed upon the bar if one of the grate sections 25 should become broken without removing the bar.

The invention consists in certain novel features of construction and combinations of parts which will be hereinafter described 30 and pointed out in the claim.

In the accompanying drawings—Figure 1 is a view in perspective showing a number of grate bars and grate sections assembled in the side bars or frame of the grate. Fig. 35 2 is a longitudinal section showing the manner of attaching the grate sections to the grate bar. Fig. 3 is a side view of the grate bar, and showing the shaker arm connected thereto. Fig. 4 is a view in side elevation of 40 one of the grate sections. Fig. 5 is an end view of one of the grate sections. Fig. 6 is a view disclosing the manner of applying the grate sections to the grate bars, and Fig. 7 is a view disclosing the manner in which the 45 grate bars are removed from the grate frame.

A, represents the side bar of a grate, and B the central bar. The central bar B is formed so that the entire set or series of 50 grate sections and grate bars can be connected up instead of forming grate bars in such lengths as to run the entire width of the oven, and thereby dividing the oven by the central bar B, which is provided with 55 means for supporting the grate bars on both sides thereof. Sockets 1, 1 are formed

on one side of the bar A, and on both sides of the central bar B, and are open at the top made in U-shaped formation.

The grate bar C is made of a flat piece of 60 metal of sufficient width and is provided with rounded ends 2, 2, which form bearings for the grate bar. The rounded ends 2 are received in the vertical sockets 1, 1 of the bars A and B. Along one side of the 65 grate bar C a rounded key 3 is formed, which extends approximately the entire length of the grate bar. At one end of the grate bar the key is cut off a short distance from the end, as at 4. At the end of the grate bar 70 where the key is cut off the rounded end 2 has a portion of the inner end thereof cut off, on both sides of the bar C, as at 5, and the cutaway portion slopes from the top of the bar to the bottom, thereby permitting 75 the grate sections to be placed obliquely upon the bar and then brought to an upright or vertical position and the key 3 to enter the groove 8 of the grate sections as 80 the grate sections are slid along upon the bar 85 into position.

The grate sections 6 are made in the usual formation, being large at the top and narrow and inclining from the ends toward the base. The grate sections are provided with 85 slots 7 which are formed at the base of the grate sections. The walls of slots 7 are straight, and the top of the slot is always straight. On one of the side walls of the slot, a curved groove 8 is formed. The 90 grate section is adapted to be placed upon the grate bar C, and the slot 7 conforms to the shape of the grate bar, making a snug fit. The curved groove 8 receives the key 3 thereby locking the grate sections upon the 95 grate bar. The grate sections are placed upon the grate bar in this manner and are all locked by the key 3. The last grate section which is placed upon the grate bar is held thereon by the key 3, but as the end 100 of the key is cut off a short distance at this end, the grate section will not engage the key the entire width of the grate section, but will receive only a partial engagement, and this engagement is sufficient for retaining 105 the grate section in place upon the bar.

The shaker arm 9 extends downwardly from the base of the grate bar C, and is provided at its lower end with a stud 10. Connecting the shaker arms 9 of the several 110 grate bars C is a reach bar 11, which is provided with openings 12, through which

2
studs 10 are received. The reach bar 11 is connected to a shaker or lever (not shown) at the end of the furnace, whereby the grate bars and grate sections are rocked, and this 5 movement does not break up the fire, but merely cleans the under side of the fire, permitting the loose ashes and small cinders to drop between the grate sections into the ash pit. The grate sections are of such 10 shape and being narrow at the top, permit a large air space on the underside of the fire.

When it is desired to remove a grate bar from the grate, the end of the grate bar which is free is raised, which permits the 15 stud 10 of the shaker arm 9 to become disengaged from the reach bar 11, and after the shaker arm is released from engagement with the reach bar 11, the grate bar and grate sections can be easily removed by 20 simply raising them from the grate frame without in any wise interfering with any of the other grate bars or grate sections, or the grate frame.

From the foregoing it will be seen that I 25 have provided a grate, any grate bar of which may be removed therefrom at any time without in any wise interfering with the other arms or grate sections of other 30 grate bars, or with the grate frame, and further that the grate sections may be placed upon or removed from the grate bar when such bar is in position without disturbing the position of such grate bar or any other 35 grate bar, or the grate frame, or reach bar, and when placed on the bar such grate section will be fastened thereon. In case of

any of the grate sections becoming broken upon a grate bar, the other grate sections can be moved along the bar and an additional grate section or grate sections can be placed 40 upon the bar while in position without otherwise interfering with the other grate sections or other grate bars. The engagement of the grate sections with the grate bars is such that the grate section is supported 45 on the bar by the bar being practically entirely received within the vertical slot of the grate section and one wall of the slot being provided with the groove in which the key 3 of the grate bar is received whereby the bar and grate section are connected together, the grate section being received upon the bar in this manner, prevents any lateral or endwise strain upon the grate section.

Having fully described my invention, 50 what I claim as new and desire to secure by Letters Patent is:—

In a grate, the combination with a grate frame, of grate bars mounted thereon, a key 60 formed on the grate bars, one end of the grate bars having an oblique cutaway portion, and grate sections mounted on the grate bars by placing them upon the cutaway portion of the grate bars and then sliding them along the bars and on the keys for 65 locking them in position.

In testimony whereof I affix my signature, in the presence of two witnesses.

ARTHUR W. HULSON.
